BUCKLE

Frank Ostolaza, Ladue, Mo., assignor to International Hat Company, St. Louis, Mo., a corporation of Missouri

Filed June 26, 1961, Ser. No. 119,673
1 Claim. (Cl. 24—198)

The present invention relates to a buckle for garments, and more particularly to a buckle used to connect the free ends of straps such as hat bands, belts or the like.

One of the principal objects of the present invention is to provide a buckle by means of which the length of a hat band can be adjusted and which will retain its adjusted length.

Another object of the present invention is to provide a buckle which does not twist causing the strap to bunch up when the strap is tightened, regardless of the direction of force applied to the strap. Still another object of the present invention is to provide a belt buckle which will release the belt when one lip of the buckle is raised.

Another object is to provide a buckle having a circular center opening and transverse slots through which a woven webbing or tape is laced so that the webbing is firmly held and will not slip when either end of the tape is pulled, regardless of the thickness of the webbing.

These and other objects and advantages will become apparent hereinafter.

The present invention comprises a buckle having an arcuate center opening bounded by transverse slots with the buckle being transversely bent in the vicinity of the slots to more firmly retain the free ends of a band of material therein, thereby adjustably linking the free ends of the band together.

In the drawings, wherein like numerals refer to like parts wherever they occur:

FIG. 1 is a perspective view showing the buckle linking the free ends of a strip of material;

FIG. 2 is an enlarged sectional view taken along line 2—2 of FIG. 1;

FIG. 3 is a sectional view similar to FIG. 2 but showing one lip of the buckle raised to free the strips of material;

FIG. 4 is an enlarged sectional view taken along line 4—4 of FIG. 1;

FIG. 5 is a side elevational view of the present invention;

FIG. 6 is a top plan view of the present invention; and

FIG. 7 is an end elevational view of the present invention.

FIG. 1 shows a buckle 10 engaged with and linking together the free ends 11 and 11a of a strip of material 12. The material 12 can be a strip of textile, leather or other material. The buckle 10 is formed with a rectangular body 13 having curved end margins 14. A circular opening 15 is provided in the center of the buckle body 13 and transverse slots 16 having outer transverse sides 16a and inner transverse sides 16b are provided in the body 13 between the opening 15 and the end margins 14. Internal ribs 17 space the slots 16 from the center opening 15, while transverse bars 18 space the slots 16 from the lip margins 14 of the body 13. Longitudinal bars 19 define the side margins of the buckle 10 and connect the ends of the ribs 17 and the end bars 18 to enclose the opening 15 and the slots 16.

The longitudinal side bars 19 are bent in a convex shape, while the intermediate ribs 17 and the transverse bars 18 are bent in a concave shape so that the transverse slot edges 16a and 16b are displaced downwardly in a vertical direction from the arcuate opening 15 and the buckle lip margin 14, respectively.

2

The buckle body 13 can be made of metal or plastic or any similar suitable material.

In use, the free ends 11 and 11a of the band 12 are inserted through the center opening 15 of the buckle 10 from below. The ribbon ends 11 and 11a are passed over the intermediate bars 17 and are returned through the slots 16 from above. The ends 11 and 11a are then aligned with the remainder of the belt 12 and pulled tightly about the object enclosed by the belt 12 until there is a slight tension in the belt 12. The ends 11 and 11a then can be released and the tension in the belt 12 will lock the belt 12 and the buckle 10 in a fixed position. To release the buckle 10, one lip 14 thereof is raised and the belt 12 is freed from the buckle 10. The locking action will be explained more fully hereinafter. The size of the slots 16 is determined by the thickness of the band 12 and the material 12 should fit snugly in the slots 16.

The round center opening 15 of the buckle 10 in combination with the straight transverse slots 16 causes the buckle 10 to be centered and axially aligned with the band 12, even when the band 12 is tightened by a force which is not directed along the longitudinal axis of the buckle 10. In other words, even if an end of the belt 12 is pulled with a force which is not axially aligned with the longitudinal axis of the buckle 10, the belt 12 will not bunch in one corner of the center opening 15, but will be aligned with the longitudinal axis of the buckle 10, since the pulling force is even all around the opening 15 and is not directed toward one corner as is the case with rectangular center openings in conventional buckles.

This is an important advantage, since the bands 12 often are hastily positioned with the free ends 11 and 11a not being pulled straight and aligned with the buckle 10 and the main portion of the belt 12. If the buckle 10 does not align itself with the main portion of the band 12, the normal locking action of the buckle 10 is not effective to link the free ends 11 and 11a of the band 12, and the band 12 may come loose.

As hereinbefore mentioned, in linking the free ends 11 and 11a of the strap 12, each of the ends 11 and 11a is threaded from below through the buckle center opening 15; is passed over the intermediate rib 17; is threaded through the transverse slot 16 between the transverse slot edges 16 and 16a; and then is aligned with and on top of the remainder of the strap 12. The strap ends 11 and 11a are pulled until there is a tension in the main portion of the strap 12. When the ends 11 and 11a are released, there is a force in the strap 12 pulling along the length of the strap 12 in a direction away from the buckle 10. The main or body portion of the strap 12 is engaged with the center opening 15 and bears against the under side of the strap ends 11 and 11a at a point aligned with the slot edges 16a thereby urging the ends 11 and 11a into engagement with the slot edges 16a most removed from the center opening 15 to lock the strap ends 11 and 11a in the buckle 10. Since the slot edges 16a are displaced from the plane of the buckle 10, the tension in the strap 12 causing the strap 12 to bear against the ends 11 and 11a tends to lock said ends 11 and 11a against said edges 16a in a fixed position in the buckle 10.

To release the strap 12, one lip 14 of the buckle 10 is raised (FIG. 3), thereby releasing the locking force exerted on one of the strap ends 11 or 11a by moving the slot edge 16a away from the immediate vicinity strap 12.

Thus it is seen that the present invention provides a buckle having a circular center opening and transverse straight slots spaced therefrom, with the edge of the slots being displaced from the plane of the buckle, said buckle

being self-aligning and self-locking with a minimum of effort and care on the part of the user.

The completely open center opening of the present buckle provides ease in applying the buckle to a strap and also provides for ease in adjusting the length of the strap. Another advantage of the present buckle is that different thicknesses of webbed belting can be used with the same buckle rather than making a separate buckle for each thickness of webbing, and thus a considerable saving in time and cost are effected.

From the foregoing it is apparent that the present invention provides a buckle which achieves all the objects and advantages sought therefor.

This invention is intended to cover all changes and modifications of the examples of the invention herein chosen for purposes of the disclosure, which do not constitute departures from the spirit and scope of the invention.

What is claimed is:

A buckle comprising a body portion provided with a circular open center area and a pair of smooth-edged straight transverse slots, one of which is positioned between the center open area and each end margin of the buckle, said body portion including a pair of convex longitudinal side bars, a pair of transverse end bars connect-

ing the side bars at each extremity thereof, the innermost edges of said end bars being concave and displaced below the side bars and the outermost edges of the end bars, said innermost edges defining a first transverse edge of the transverse slots, and transverse intermediate bars connecting the side bars, the outermost edges of the intermediate bars being concave and displaced downwardly from the plane of the buckle a lesser amount than said innermost edges of said end bars, said outermost edges of said intermediate bars defining second transverse edges of the transverse slots, the innermost edges of said intermediate bars being spaced from each other and of arcuate shape and defining a portion of the peripheral edge of the circular open center area.
